LAPPING MACHINE

George E. Hulbert and Herbert S. Indge, Westboro, Mass., assignors to Norton Company, Worcester, Mass., a corporation of Massachusetts

Original application May 23, 1936, Serial No. 81,372. Divided and this application May 18, 1938, Serial No. 208,629

4 Claims. (Cl. 51—118)

This invention relates to lapping machines, and more particularly to an improved work cage construction therefor. This application is a division of our copending application Serial No. 81,372 filed May 23, 1936, which has issued as U. S. Patent No. 2,142,057 dated December 27, 1938.

One object of the invention is to provide a simple and thoroughly practical lapping machine. Another object of the invention is to provide a lapping machine with a work carrying cage which is arranged to facilitate rapid removal and loading of work pieces. Another object of the invention is to provide an improved cage for a lapping machine which may be readily loaded from a single operating station. A further object of the invention is to provide a cage construction in which the cage may be readily indexed to facilitate loading the same from a single station in front of the machine. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Figure 1 is a side elevation of a lapping machine, having parts broken away and shown in section more clearly to show the construction;

Figure 2 is a plan view, on an enlarged scale, of the work carrying cage, having parts broken away and shown in section more clearly to show the construction;

Figure 3 is a cross sectional view taken approximately on the line 3—3 of Figure 2;

Figure 4 is a fragmentary plan view, on an enlarged scale, of a modified form of locking device for the work carrying cage; and

Figure 5 is a fragmentary cross sectional view taken approximately on the line 5—5 of Figure 4.

A lapping machine has been illustrated in the drawings which comprises a base 10 having a vertically extending support 11 on which is mounted a supporting arm 12 for an upper lapping wheel 13. The lapping wheel 13 is supported by a plate 14 which is fixed to the lower end of a slidably mounted rack bar 15. The upper lap 13 may be raised and lowered by means of a spoked wheel 16 which is mounted on one end of a rotatable shaft 17. The shaft 17 carries a gear (not shown) which meshes with the

teeth on the rack bar 15 and serves, when the spoked wheel 16 is rotated, to raise or lower the upper lap 13.

In order to hold the lapping wheel 13 in an upper or inoperative position, a ratchet wheel 5 is mounted on the end of the shaft 17 and is arranged to be engaged by a pawl 21 pivotally mounted on a stud 22 which is supported on the arm 12.

A lower lapping wheel 30 is supported by a flanged plate 31 which is keyed to a rotatable sleeve 32 which is journaled in bearings 33 and 34 in the base 10. The sleeve may be rotated in the manner shown in the prior United States patent to Indge No. 1,610,527, to which reference 15 may be had for a more detailed disclosure. A tight pulley 35 and a loose pulley 36' are mounted on the outer end of a drive shaft 36 which is rotatably supported in bearings 37 and 38 in the base 10. The shaft 36 carries a worm 39 which meshes with a worm gear 40 keyed to the rotatable sleeve 32. When a driving belt (not shown) is shifted from the loose pulley 36' onto the tight pulley 35, the shaft 36 and worm 39 are rotated, thereby transmitting a rotary motion to the sleeve 32, the plate 31 and the lower lap 30.

A cage structure 49 is mounted between the lapping wheel 13 and the lapping wheel 30 and is provided with apertures which are shaped to receive work pieces to be lapped. As shown in Figure 2, the cage structure 49 is provided with a plurality of circular work receiving apertures 51 which serve to locate and hold a plurality of work pieces 52 within the cage structure 49 for a lapping operation. The apertures 51 may be square or of any other irregular shape which may correspond in design with the shape of the work piece to be lapped.

In order to provide a desired lapping action 40 between the work pieces and the relatively rotated lapping elements, the cage structure 49 is provided with a mechanism for gyrating the work carrying cage 50 so as to continuously change the relation of the work and the relatively rotatable lapping wheels. For this purpose a head 55 is keyed to the upper end of a rotatable sleeve 56, the rotatable sleeve 56 being provided with bearings 57 and 58 which rotatably fit on a stationary vertically extending shaft 59 which is keyed to a projection 60 of the base. The sleeve 56 is mounted in bearings 61 and 62 which are supported in the rotatable sleeve 32 so that the sleeves 32 and 56 may rotate relative to each 50 45 55 50 55

other and relative to the stationary central shaft 59.

A gear 65 is keyed to the lower end of sleeve 32 and meshes with a gear 66 which is keyed to 5 a bushing 67 rotatably mounted on a fixed stud 68. A gear 69 is also keyed to the bushing 67 and meshes with a gear 70 which is keyed to the lower end of the inner sleeve 56 and serves to 10 rotate the head 56 at a slightly different speed from the rotation of the lap 30.

A gear 70 is keyed to the upper end of the stationary shaft 59 and meshes with a plurality of spaced pinions 71 which are rotatably supported on studs 72. The studs 72 are mounted 15 on the rotatable head 55. The pinions 71 are formed integral with rotatable heads 73 each of which carries a driving or crankpin 74. In the construction illustrated there are three pinions 71 which are symmetrically spaced about the 20 central shaft 59 and each of which carries a crankpin 74 which are arranged to engage apertures 75 (Fig. 3) within the cage 50. When the drive shaft 36 is rotated to transmit a rotary motion to the lower lap 30, the rotation of the 25 sleeve 32 transmits a rotary motion through the gear 65, the gear 66, the gear 69, the gear 70 and the sleeve 56 to rotate the head 55 which serves to revolve the studs 72 about the central stationary shaft 55. The geared connection between the stationary shaft and the heads 73, 30 which includes the gear 70 keyed to the upper end of the shaft, serves to rotate the pinions 71 during the revolution of the studs 72 and cause a rotation of the heads 73 to transmit a combined rotary and gyrating movement to the cage to carry the work pieces through an irregular path between thelapping wheels for a lapping operation. The construction thus far described is identical with that shown in the prior patent to Indge No. 1,610,527 dated December 14, 1926, 40 to which reference may be had for a more detailed disclosure.

While the machine illustrated and above described shows an upper stationary lap which is moved vertically toward and from a lower rotatable lap, this invention is equally applicable to other types of lapping machines in which either or both of the lapping wheels are rotatable and movable toward and from each other.

In the operation of a lapping machine, especially a lapping machine in which the cage and the lapping wheels are of relatively large diameter, it is desirable to provide a means for readily loading the cage, that is removing the finish lapped work pieces therefrom after a lapping operation and inserting new pieces of work in the machine from a single operating station in front of the machine, thereby facilitating the loading of the machine. In the preferred construction the cage structure 49 is preferably formed in two parts, an outer work carrying cage 50 which is provided with work receiving apertures 51, and an inner supporting member 79. The supporting member 79 comprises a pair of spaced plates 80 and 81 which are held in spaced relationship 55 with each other by means of a plate 82. The plates 80, 81 and 82 are held in fixed relationship with each other by studs 83 which pass through holes in the plates. The three plates 80, 81 and 82 form an annular groove 84 which serves to 60 rotatably support the work carrying cage 50.

It is desirable to provide a suitable driving connection between the work carrying cage 50 and the central supporting member 79 so that during a lapping operation, the work carry-

ing cage 50 and its inner supporting member 79 may be rotated and gyrated simultaneously by the mechanism above described. The work carrying cage 50 is provided with an inner internal aperture 85 which is a clearance hole there-through so as to permit free rotation of the work carrying cage 50 relative to the supporting member 79.

In the preferred construction, a pawl and ratchet mechanism is interposed between the 10 work carrying cage 50 and its central supporting plates 80, 81 and 82. The work carrying cage 50 is provided with a plurality of notches 87 which are arranged to be engaged by a plurality of spaced pawls 88 which are pivotally mounted on 15 studs 89. A spring 90 is carried by the inner plate 82 and is arranged to exert a pressure tending to turn the ratchet pawls 88 in a clockwise direction to hold the pawls 88 in engagement with the notches 87 so that when the supporting member 79 is rotated in the direction of the arrow, as shown in Figure 2, the pawls 88 carried by the central supporting member 79 will drive the work carrying cage 50 so that they rotate and gyrate simultaneously.

The central supporting member 79 is provided with three spaced bushings 100 each of which is provided with a pin receiving aperture 105 which are adapted to engage the driving pins 74. The bushings 100 pass through the three plates 80, 81 and 82 and are held in adjusted position therein by means of nuts 101. Each of the bushings 100 is provided with an adjusting screw 102 which is adapted to bear against the upper end of the crankpin 74 and serves to adjust the position of 30 the supporting member 79 and work carrying cage 50 relative to the lower lap 30 so that the work carrying cage 50 may be adjusted close to or spaced from the operative surface of the lap 30, depending upon the thickness of the work pieces which are to be lapped. The adjusting screws 102 are held in adjusted position by lock nuts 103 so that after the screws have been adjusted to position the work carrying cage 50, as desired, the locking nuts 103 may be tightened to lock the 40 cage in its adjusted position.

After the lapping operation has continued on a plurality of work pieces 52 so that they have been lapped to the desired extent, the rotation of the lapping wheels 13 and 30 is then stopped 50 by shifting the driving belt (not shown) from the tight to the loose pulley, and the wheels are thereafter separated from each other. The work piece adjacent to the loading station is then removed from the machine and a new piece of work 52 is inserted thereinstead, and the work carrying cage member 50 may then be rotated relative to the supporting member 79 by manually rotating the work carrying cage 50 against the ratchet pawls 88 in a counterclockwise direction 60 (Fig. 2) so that the next cage aperture may be loaded from the same position in front of the machine. After the second station has been loaded, the work carrying cage 50 may be further rotated, and so on until all of the finish lapped pieces have been removed and new pieces 65 to be lapped inserted thereinstead for another lapping operation.

A modified form of locking device has been 70 illustrated in the modification shown in Figures 4 and 5. As indicated in the modification, the work carrying cage 50 is provided with a notch or recess 120 which is arranged to be engaged by a slidably plunger 121 which slides within a radially extending slot 122 in the plate 82. The 75

plunger or locking pin 121 is connected by a pivot pin 123 with a strap 124 which surrounds a rotatable eccentric plate 125. The eccentric plate 125 is rotatably supported between the plates 80 and 81. A projecting hub 126 serves as a trunnion to support the upper end of the eccentric plate, and a stud 27 passing through an aperture in the lower plate 81 serves as a trunnion to rotatably support the eccentric 125. When it is desired to lock the supporting member 79 and the work carrying cage 50 together for a lapping operation, a manually operable handle 130 is moved into the full line position, as shown in Figure 4, so that the eccentric plate 125 moves the plunger 121 downwardly into engagement with the notch 120 so as to lock the work carrying cage 50 to the plates 80, 81 and 82 so that they may be rotated and gyrated simultaneously. When the work pieces have been lapped to a predetermined extent, and the laps have been separated to an inoperative position, the handle 130 is moved into the dotted line position 130a (Fig. 4) which serves to rotate the eccentric 125 into the dotted line position 125a and thereby to withdraw the plunger 121 from the notch 120 so that the work carrying cage 50 may be rotated relative to the supporting member 79 for unloading and loading of work pieces.

The operation of this lapping machine is readily apparent from the foregoing disclosure. Assuming the lapping wheels 13 and 30 to be separated in an inoperative position, the work carrying cage 50 is rotated manually relative to the supporting member 79 from an operating station in front of the machine and a work piece 52 is inserted in each of the apertures 51, after which the driving belt is shifted from the loose to the tight pulley to start a relative rotation between the lapping wheels and at the same time to start the rotation and gyration of the supporting member 79 and the work carrying cage 50 to simultaneously lap a plurality of work pieces to a predetermined extent. After the work pieces have been lapped to the required extent, the laps are again relatively separated from the work pieces and the lapped work pieces are removed therefrom and new pieces inserted therein as the work carrying cage 50 is rotated relative to the supporting member 79, thereby facilitating loading of the machine and enabling a machine of large diameter to be loaded from a single operating station in front of the machine.

It will thus be seen that there has been provided by this invention apparatus in which the various objects hereinabove set forth together with many thoroughly practical advantages are successfully achieved. As many embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. A lapping machine comprising a pair of opposed lapping wheels, means to relatively rotate said wheels, means to move said wheels relatively toward and from each other, a cage supporting member, means to move said cage supporting member through an irregular path relative to said lapping wheels, a work carrying cage rotatably supported on said member, and a manually operable slidably driving plunger releasably to lock said cage to said supporting member so as synchronously to move said cage with said member when the member is moved in an irregular path for a lapping operation.

2. A lapping machine comprising a pair of opposed relatively rotatable lapping wheels, means to relatively rotate said wheels, means to cause a relative approaching or receding movement therebetween, a cage supporting member, means to move said support through an irregular path relative to said relatively rotatable lapping wheels, a work carrying cage having a plurality of work receiving apertures which is rotatably mounted on said support, locking means including a slidably mounted plunger interposed between said support and cage releasably to lock the cage to the support so that the cage is synchronously moved through an irregular path with the support for simultaneously lapping a plurality of work pieces, and manually operable means including a cam to actuate said locking plunger to permit rotation of said cage to facilitate loading of the same.

3. A work support for a lapping machine comprising a central supporting member which is arranged for an irregular movement, a work carrying cage having a plurality of work receiving apertures which is rotatably supported thereon, means to move said member in an irregular path, and means including a manually operable cam actuated plunger to lock said cage to said member during a lapping operation so as to move said cage in synchronism with said member when the supporting member is moved through an irregular path.

4. A work support for a lapping machine comprising a central supporting member which is arranged for a gyrating movement, a work carrying cage rotatably supported thereon and having a plurality of work receiving apertures therein, means including a releasable slidable plunger to lock said work carrying cage to said supporting member so that the cage moves in synchronism with said supporting member, and means including a manually operable lever operatively connected to actuate said locking plunger so as to permit a rotation of the cage to facilitate loading of the same when the supporting member is stationary.

GEORGE E. HULBERT. 60
HERBERT S. INDGE.
